UNITED STATES PATENT OFFICE

CARL LOUIS BACH, OF LIMBACH, GERMANY

DRIVING MECHANISM FOR INTERMITTENTLY-ROTATING SHAFTS

Application filed July 2, 1926, Serial No. 120,234, and in Germany July 16, 1925.

My invention relates to improvements in driving mechanisms for intermittently rotating shafts such as are used for example in sewing-machines for jointing knitted fabrics or the like or in chain-stitching-machines used for similar purposes. As is known to those skilled in the art in machines for jointing knitted fabrics the fabrics are fed and brought into stitching position by means of feed rolls. The shafts or axes of the said rolls are connected with each other by gear wheels so that only one of the axes need be connected with the driving mechanism. In chain-stitching-machines intermittent movement is imparted to the needle disk. In both cases intermittent movement is imparted to the driven members in order that the fabric is at rest at certain moments for stitching the needle into the same and retracting the same therefrom.

Machines of the class referred to are operated at high velocity, the number of the stitches per minute being as high as 4000. Therefore the feed rolls have very high velocities, so that it is difficult to provide reliable mechanisms for imparting intermittent movement thereto, so much the more as the feed movement must be very exact, because otherwise the length of the stitches is different. Therefore the driving mechanism must be such that the axis of the feed rolls follows exactly the movement of the driving mechanism, and that it is arrested exactly when the movement of the driving mechanism is arrested or reversed, without being further moved by inertia, because any excess of the movement of the rolls beyond the movement of the driving mechanism cannot be controlled and is never alike.

The object of the improvements is to provide a driving mechanism of the character referred to which is exact in operation even at high velocity, and with this object in view my invention consists in connecting the axis of the feed rolls with the driving mechanism through the intermediary of a free-wheel mechanism, one of the members of the said mechanism receiving reciprocating movement from the driving mechanism, while the driven member takes part in such movement

in one direction only. Further, for directly arresting the driven member when the driving stroke of the driving member is finished, clamping means are provided for arresting the driven member, by means of which the movement of the axis and the feed roll or needle disk is immediately interrupted when the driving member completes its driving movement.

Fig. 1 is an elevation partly in section showing one form of the driving mechanism,

Fig. 2 is a bottom view of Fig. 1 looking in the direction of the arrow 5,

Fig. 3 is a sectional elevation taken on the line 6—6 of Fig. 2,

Fig. 4 is a detail view showing the main parts of the free-wheel mechanism and the clamping means therefor, and

Fig. 5 is a perspective view of the clamping means for resting the driven member.

On the shaft 8, which is adapted to carry one of the feed rolls, a gear wheel 9 and a ring 10 are mounted, the gear wheel 9 being made integral with the ring 10 or fixed thereto by means of a screw 11. Within the ring 10 a disk 12 is loosely mounted on the shaft 8, which disk is formed with three notches 13 having their bottom faces disposed eccentrically of the axis 8 and the inner circumference of the ring 10. In each of the said notches there is a roller 14 and the said rollers are held in contact with the bottom faces of the notches and the inner face of the ring 10 by means of one or more springs 15. To the disk 12 a plate 17 is fixed by means of screws 16, and the said plate confines the rollers 14 within their notches and is made integral with an arm 18 adapted to be reciprocated from the driving mechanism of the machine as has been indicated by the numerals I and II shown in Fig. 2. All the parts so far described are held in position on the axis 8 by means of a ring 20 fixed to the shaft 8 by means of a screw 19.

To the bottom face of the frame 24 two rails 21 and 22 are secured, and between the said rails an arm 25 is rockingly mounted, which arm is fixed to a curved spring 26 secured to the rail 22, the said spring tending to rock the arm 25 around the edge 23 of

the rail 22. The tension of the spring 26 is regulated by means of a screw 30. The arm 25 is formed with a notch 27 by means of which it embraces the ring 10 from the bottom side thereof, the disk 12 and plate 17 being formed with a notch 29 permitting the rocking movement of the disk 12 and the plate 17 without interfering with the arm 25. The arm 25 and spring 26 are held in position by means of a plate 31 secured to the bottom faces of the rails 21 and 22 by means of screws 32.

By the pressure of the spring 26 on the arm 25 the inner and outer edges of the notch 27 are held in contact with the outer and inner circumferential faces of the ring 10, so that the arm 25 and the spring 26 provide a clamping mechanism of simple construction. The rotary movement imparted to the ring 10 by the disk 12 through the intermediary of the rollers 14 is not materially affected by the engagement of the arm 25 with the inner and outer faces of the ring 10, because when imparting rotary movement to the ring 10 the arm 25 is slightly rocked in a direction for releasing the frictional pressure on the ring 10. But when the disk 12 is at the end of its operative stroke and the clamping engagement of the rollers 14 with the ring 10 is interrupted, the frictional engagement of the end walls of the notch 27 with the ring 10 is sufficient instantaneously to arrest the ring 10 and the axis 8 and to prevent further rotary movement of the said parts by impact.

In constructions of the class referred to the masses to be accelerated and retarded are small. Therefore, during the forward movement of the ring 10 the braking action of the arm 25 is not objectionable, but it is sufficient for instantaneously arresting the movable parts as soon as the driving power is relieved.

While in describing the invention reference has been made to a particular example embodying the same I wish it to be understood that my invention is not limited to the constructions shown in the drawings, and that various changes may be made in the general arrangement of the apparatus and the construction of its parts without departing from the invention.

I claim:

1. Means for preventing return movement of an intermittently revolved member, comprising in combination, a cylindrical member secured to said intermittently revolved member, a pair of rails fixedly mounted at one side of the axis of rotation, a lever member yieldingly mounted therebetween, having a notch with parallel walls adapted to engage the inner and outer surfaces of said cylindrical member, said lever member operating to yield and permit motion of said cylinder in one direction, but operating to automatically clamp said cylinder between its walls

and prevent motion in the opposite direction.

2. An automatic one-way brake comprising in combination a rotatable cylindrical member, a pair of fixedly mounted supports, a spring secured to one of said supports, an adjustable abutment for said spring on the other of said supports, and a lever mounted on said spring, one end of said lever normally engaging one of said supports, said lever being provided with a notch for engaging said cylindrical member.

3. An automatic one-way brake comprising in combination a rotatable element, means adapted for movement into one position for frictionally retarding rotation of said element in one direction and movable out of said position by rotation of said element in the opposite direction, a spring for supporting said means and for normally urging the same into element retarding position, and an adjustable support for said spring for regulating the degree of frictional contact between said means and said element.

In testimony whereof I hereunto affix my signature.

CARL LOUIS BACH.
